UNITED STATES PATENT OFFICE.

FREDERICK KALMBACH, OF NEW YORK, N. Y.

FILM-SPlicing DEVICE.

Application filed October 4, 1919. Serial No. 328,413.

To all whom it may concern:

Be it known that I, FREDERICK KALMBACH, a citizen of the United States, residing at the borough of Bronx, in the city of New York, county of Bronx, and State of New York, have invented certain new and useful Improvements in Film-Splicing Devices, of which the following is a specification, reference being had therein to the accompanying 10 drawings, which form a part thereof.

My invention relates to film splicing devices, and more particularly to a device of this character by means of which the ends of two sections of the films used in the cinematographic art may be firmly, quickly and neatly united in a manner to ensure accuracy in the spacing and alinement of the sprocket openings along opposite edges of the film.

20 A device made in accordance with my invention is so constructed that the end of the film from which the emulsion must be scraped is accurately positioned in relation to a hardened bearing surface, which will 25 not be quickly worn, through abrasion by the keen edge of the hand-tool used in removing the emulsion.

The means used for so positioning the film are so arranged as to serve as a guide 30 for a straight-edge used to hold the film flat upon the hardened surface and define the area from which the emulsion is to be scraped. The same means also serve to accurately aline the ends of the two sections 35 of film to be spliced or united, said means having associated therewith a presser mechanism which, in co-operation therewith, will force the two film sections together to ensure the proper bonding action of the cement 40 and at the same time prevent warping or distortion of the two film sections while the binding medium is setting.

Another characteristic of a device made 45 in accordance with my invention, is the association with the presser mechanism above referred to, of a clamp bar arranged at one side thereof for holding that film section from which the emulsion has been removed, firmly upon the top surface of the device, so 50 as to facilitate the proper application of the edge of the other film section thereto.

I have found in actual practice that the cement used in binding the films will attack 55 many metals and ultimately pit same in a manner to cause an uneven surface and a resultant formation of an improper splice

joint. To obviate this condition I make that portion of the table of the device co-operating with the presser mechanism of a metal immune to the action of the cement and also 60 make this portion removable from the base so that in the event of its becoming damaged or worn, it may be readily replaced.

The hardened portion of the table is also made removable so that in case of wear it 65 may be removed and a new section substituted therefor.

The presser bar or platen is so constructed as to co-operate with the guide pins in forcing and holding the two film sections in the 70 desired rectilineal relation, this mechanism being capable of being quickly applied to the film for this purpose, and means being provided whereby the desired uniform pressure may be developed upon said bar or 75 platen to ensure rapid action of the cement and the expression from between the lapped portions of the film of all cement in excess of that required to secure the desired bond, while avoiding any material increase in the 80 thickness of the film at the splice.

A device made in accordance with my invention may be used in a laboratory in making up a reel of the negative film, or in the projector booth in repairing broken films. 85

The invention consists primarily in a film splicing device embodying therein a base having a top or table divided into two end sections and a middle section, all arranged on the same plane, one end section having a 90 hardened area, a movable clamp bar adapted to act against the other end section, two sets of rectilineally arranged pins upon said middle section, and a presser mechanism associated with, and movable with relation 95 to, said middle section, embodying therein a presser platen having recesses therein co-operating with said pins, whereby said guide pins may be used to accurately position the end of one film section with relation to said 100 hardened area, and to position a straight-edge with relation to the end of said film, to facilitate the removal of the emulsion therefrom, and to position the ends of two film sections being spliced with relation to 105 each other and to said presser mechanism, to facilitate the making of a lap joint between said ends; and in such other novel features of construction and combination of parts as are hereinafter set forth and described, and more particularly pointed out 110 in the claims hereto appended.

Referring to the drawings,

Fig. 1 is a perspective view of a film splicing device made in accordance with my invention, a straight-edge and a knife 5 scraper being shown in position for removing the emulsion from the end of a film section, the clamp bar being shown in the raised position in dotted lines;

Fig. 2 is a plan view thereof showing two 10 sections of film thereon with the presser mechanism broken away; and

Fig. 3 is a rear view partly in elevation and partly in longitudinal section, on the line 3—3 of Fig. 2.

Like letters refer to like parts throughout the several views.

In the embodiment of my invention shown in the drawings, I employ a metal base *a* having suitable perforated extensions *a'* at 20 the opposite sides thereof to facilitate the mounting of the device upon a bench. The top or table of this base is formed of two end sections *b*—*d* and a middle section *c*. The end section *b* is formed integrally with 25 the base *a*. The other end section *d* is in part formed therewith and in part formed by a hardened steel block *d'*, detachably secured to the base *a* by means of the screw *d''*. The middle section *c* is formed of a 30 white metal alloy having a base of zinc, tin or aluminum, or composed of other material having no affinity with, or immune to the action of, the cement used in joining sections of the film.

The section *c* is detachable from the base *a*, being secured in place by means of the screw *c'*.

Carried by, or formed integrally with, the middle section *c* are two pairs of pins *e*—*e'* and *f*—*f'* adjacent opposite ends of said section. The pins of each pair are rectilinearly arranged as to each other and as to the corresponding pins of the other pair, the pins of each pair being spaced apart a 45 distance equal to that between the sprocket openings along opposite edges of the film, and the pins of one pair are spaced away from those of the other pair a distance sufficient to permit their being engaged with next to 50 the end sprocket opening in each film section being spliced, so that when the two end sections are brought together, the films will be held in alinement, and sufficient space will be afforded between the pins to prevent 55 their being fouled by the cement used in forming the joint.

The ends of the pins are tapered slightly to facilitate the mounting of the film sections thereon, the base of the pin adjacent 60 the surface of the section *c*, however, being of substantially the same dimension as the sprocket opening in the film, so that there can be no such lateral or longitudinal deflection of the film, while forming the joint, as 65 would lead to the buckling or distortion of

the film or a loss of alinement of the spliced sections.

Pivoted at one end of the section *b* is a clamp bar *g* having an angular projection *g'* thereon engaged by a spring pressed plunger *g''* mounted in the base *a*, so that when this clamp bar is raised from said section, it will be held raised by said spring pressed plunger and when it is moved toward said section, it will be forced into and maintained in the set position, firmly holding the film upon said section.

Pivotedly mounted in suitable lugs *a''* upon the base *a*, so as to be adapted to be projected across the section *c*, is a bar *h* having pivoted thereon a presser bar or platen *i* having on the under face thereof recesses *i'* adapted to receive the guide pins upon the section *c*, the dimensions of these openings being such as to compensate for the arc described by said presser bar or platen in its movement toward or from said section *c*.

The base *a* upon the opposite end of the section *c* has pivotally mounted thereon a recessed arm *j* having mounted therein a spring pressed plunger *k* adapted, when said arm *j* is raised, to pass over, engage and press the bar *h* and the presser bar or platen *i* carried thereby, toward the section *c*. The end of the bar *h* adjacent said arm *j* is rounded as shown to facilitate the free action of said arm.

The pins *f*—*f'* in addition to serving as guides for the film when removing the emulsion from one end thereof, and when forming the splice joint, also serve as guides for the rear edge of a straight-edge *m* of hardened steel, which is used for holding the end of a film section upon the hardened area afforded by the block *d'*, and exposing only 105 that area of the film section from which the emulsion is to be removed.

Referring to Fig. 1 of the drawings, the knife or other scraper for removing emulsion is shown at *n*.

The two film sections being spliced are indicated at *o* and *p* respectively.

The operation of the herein described device is substantially as follows:—

One section of the film, such as *o*, which is to be spliced to the other section *p*, is cut at right angles to the edge of the film close to the sprocket openings of the portion of the film which is not to be used, thus leaving a continuous surface to the film from 115 edge to edge thereof, the width of which is substantially equal to the distance between adjacent sprocket openings at each edge of the film. The end of this section of film is then brought, emulsion side upward, upon the top surface of the device, with the cut end thereof upon the block *d'*, the pins *e*—*e'* and *f*—*f'* being passed through sprocket openings in this film section. The clamp bar *g* may be then moved toward the top sec- 130

tion *b* to hold the film in place upon the device. The straight-edge *m* is then placed with its rear edge against the pins *f-f'* and one end against one of the lugs *a²*, leaving exposed a narrow strip of the film of approximately one-eighth of an inch in width. The knife *n* is then used to scrape the emulsion from this exposed area of the film section, the straight-edge *m* defining the area 10 from which the emulsion can be scraped and limiting it to the distance between sprocket openings, or within the portion of the film between succeeding pictures.

When emulsion has thus been removed 15 from the end of the film section *o*, the clamp bar *g* is raised and this section of the film is repositioned by passing next to the end sprocket openings therein over the pins *e-e'*. The cement is then applied to the 20 cleaned area by means of a brush. The end of the film section *p* having been cut in the same manner as the end of the section *o*, is then lapped over the film section *o* to the extent of the area from which emulsion is 25 removed, the next to the end sprocket openings of the section *p* being passed over the pins *f-f'*.

The bar *h* is then moved toward the section *c*, the presser bar or platen *i* engaging the 30 entire area of the two film sections adjacent and between the various guide pins, forcing them into intimate contact with the section *c*. The enlargement of the guide pins toward the surface of the section *c* corrects 35 any loss of alinement of the two sections. The arm *j* is then swung over the bar *h* momentarily, the spring pressed plunger *k* developing sufficient pressure to secure the desired intimate relation of the two film 40 sections and expressing surplus cement from between the lapped ends thereof. The arm *j* is then moved out of engagement with the bar *h* and the bar raised. The film is then removed from the device and both 45 surfaces thereof wiped off with a soft cloth to remove the expressed cement. The surfaces of the top section *c* and platen *i* should then be cleaned.

The various top sections *b*, *c* and *d* of 50 the base, and the surface of the platen *i* should have a smooth finish to secure uniformity in thickness throughout the splice.

By making the section *c* in its entirety removable from the machine, this section 55 may be readily replaced in the event of deterioration or wear resulting in the loss of the desired flat, smooth surface, which condition is also true as to the hardened block *d'* of the section *d*.

By making the section *c* of a metal or a 60 metallic alloy having no affinity for, or immune to the action of, the cement, the life of this section may be much prolonged.

With a device made in accordance with my 65 invention, a perfect splice may be made

within a few seconds. While there will be a slight added thickness to the film at the point of the splice, the thickened area will be positioned between sprocket openings, so that it will not interfere in any way with 70 the free running of the film in a projector or in a printing machine.

It is not my intention to limit the invention to the precise details of construction shown in the accompanying drawings, it 75 being apparent that such may be varied, without departing from the spirit and scope of the invention.

Having described the invention, what I claim as new and desire to have protected 80 by Letters Patent, is:—

1. A film splicing device embodying therein a base having a top or table divided into two end sections and a middle section, all arranged in the same plane, one end section 85 having a hardened area, a movable clamp bar adapted to act against the other end section, two pairs of pins upon said middle section, the pins of each pair being spaced apart a distance equal to that between the 90 sprocket openings along opposite edges of the film, and being rectilinearly arranged as to each other and as to the corresponding pins of the other pair, and the pins of one pair being spaced away from those of 95 the other pair sufficiently to permit the formation of a splice therebetween, and a presser mechanism associated with, and movable with relation to, said middle section, embodying therein a presser platen having 100 recesses therein adapted to receive said pins, the pins of each pair being adjacent said end sections respectively whereby said guide pins may be used to accurately position the end of one film section with relation to said 105 hardened area, and to position a straight-edge with relation to the end of said film, to facilitate the removal of the emulsion therefrom, and to position the ends of two film sections being spliced with relation to 110 each other and to said presser mechanism, to facilitate the making of a lap joint between said ends.

2. A film splicing device embodying therein a base having a top or table divided into 115 two end sections and a middle section, all arranged in the same plane, one end section having a hardened area, a movable clamp bar adapted to act against the other end section, two sets of rectilinearly arranged 120 pins upon said middle section, said middle section being detachably connected with said base, whereby it may be renewed when necessary, and a presser mechanism associated with, and movable with relation to, said 125 middle section, embodying therein a presser platen having recesses therein cooperating with said pins, whereby said guide pins may be used to accurately position the end of one film section with relation to said hardened 130

area, and to position a straight-edge with relation to the end of said film, to facilitate the removal of the emulsion therefrom, and to position the ends of two film sections being spliced with relation to each other and to said presser mechanism, to facilitate the making of a lap joint between said ends.

3. A film splicing device embodying therein in a base having a top or table divided into 10 two end sections and a middle section, all arranged in the same plane, one end section having a hardened area, a movable clamp bar adapted to act against the other end section, two sets of rectilinearly arranged pins 15 upon said middle section, said middle section being made of material having no affinity for, or immune to the action of, the cement used in making a splice, and being detachably connected with said base, whereby 20 it may be renewed when necessary, and a presser mechanism associated with, and movable with relation to, said middle section, embodying therein a presser platen having recesses therein cooperating with said pins, 25 whereby said guide pins may be used to accurately position the end of one film section with relation to said hardened area, and to position a straight-edge with relation to the end of said film, to facilitate the removal of 30 the emulsion therefrom, and to position the ends of two film sections being spliced with relation to each other and to said presser mechanism, to facilitate the making of a lap joint between said ends.

35 4. A film splicing device embodying therein in a base having a top or table divided into two end sections and a middle section, all arranged in the same plane, a hardened metal block detachably mounted on said 40 base and forming a part of one end section, a movable clamp bar adapted to act against the other end section, two sets of rectilinearly arranged pins upon said middle section, and a presser mechanism associated with, and 45 movable with relation to, said middle section, embodying therein a presser platen having recesses therein co-operating with said pins, whereby said guide pins may be used to accurately position the end of one 50 film section with relation to said hardened area, and to position a straight-edge with relation to the end of said film, to facilitate the removal of the emulsion therefrom, and to position the ends of two film sections being spliced with relation to each other and to said presser mechanism, to facilitate the making of a lap joint between said ends.

55 5. A film splicing device embodying therein in a base having a top or table divided into 60 two end sections and a middle section, all arranged in the same plane, one end section

having a hardened area, a movable clamp bar adapted to act against the other end section, two sets of rectilinearly arranged pins upon said middle section, a bar pivotally mounted upon said base and adapted to project across said middle section, a presser platen pivotally mounted thereon, said platen having recesses therein adapted to receive said guide pins, an arm pivotally mounted upon said base, and a spring pressed plunger carried by said arm and adapted to engage said bar, whereby said guide pins may be used to accurately position the end of one film section with relation to said hardened area, and to position a straight-edge with relation to the end of said film, to facilitate the removal of the emulsion therefrom, and to position the ends of two film sections being spliced with relation to each other and to said presser mechanism, to facilitate the making of a lap joint between said ends.

6. A film splicing device embodying therein in a base having a top or table divided into two end sections and a middle section, all arranged in the same plane, one end section having a hardened area, a movable clamp bar adapted to act against the other end section, two sets of rectilinearly arranged pins upon said middle section, said middle section being made of material having no affinity for, or immune to the action of, the cement used in making a splice, and being detachably connected with said base, whereby it may be renewed when necessary, a bar pivotally mounted upon said base and adapted to project across said middle section, a presser platen pivotally mounted thereon, said platen having recesses therein adapted to receive said guide pins, an arm pivotally mounted upon said base, and a spring pressed plunger carried by said arm and adapted to engage said bar, whereby said guide pins may be used to accurately position the end of one film section with relation to said hardened area, and to position a straight-edge with relation to the end of said film, to facilitate the removal of the emulsion therefrom, and to position the ends of two film sections being spliced with relation to each other and to said presser mechanism, to facilitate the making of a lap joint between said ends.

In witness whereof I have hereunto affixed my signature, in the presence of two subscribing witnesses, this 29th day of September, 1919.

FREDERICK KALMBACH.
